UNITED STATES PATENT OFFICE.

CHARLES PASQUIER, OF NEW YORK, N. Y.

COLLIER.

1,059,201.

Specification of Letters Patent. Patented Apr. 15, 1913.

Application filed July 15, 1912. Serial No. 709,370

To all whom it may concern:

Be it known that I, CHARLES PASQUIER, a citizen of France, residing at New York city, in the county of New York and State of New York, have invented new and useful Improvements in Colliers, of which the following is a specification.

The general object of the invention is to facilitate and expedite the operation of coaling a ship while at sea and under way, or while in a harbor and at anchor. And to this end the invention consists in a collier arranged so as to receive or surround the ship to be coaled and having coal pockets arranged so as to discharge their contents into the bunkers of the ship.

Other objects will appear and be better understood from that embodiment of my invention of which the following is a specification, reference being had to the accompanying drawings forming part hereof in which:

Figure 1 is a side elevation of the device. Fig. 2 is a plan. Fig. 3 is an end elevation. Fig. 4 is a sectional detail of one of the clamps and a fragment of the buffer. Fig. 5 is a detail section of one of the conduits.

The collier designated generally by α , is by preference constructed so as to receive the ship to be coaled in the manner following that in which a dry-dock receives a ship to be docked. For this purpose the opposite sides 5—5 of the collier are arranged sufficiently far apart so as to accommodate ships of relatively great beam, the said sides 5—5 are in the form of huge floats and their upper decks are sufficiently far above the water line and above the inlets to the coal bunkers of a ship to admit of the hopper shaped coal pockets 6—6, which are arranged on the upper decks of the sides 5—5, discharging their contents into the said coal bunkers through the pipes or conduits 7—7 which are adjustably connected to the lower ends 45 of the hoppers. The pipes or conduits 7—7 may be of any preferred construction and are preferably formed of sections connected together for universal movement so as to facilitate the introduction of the said pipes 50 into coal bunkers of the ship or to such other part of the ship as is desired to receive the coal.

The forward ends of the sides 5—5 are connected by the angular-shaped bow portion 8 which is constructed so as to be buoyant like the sides 5—5.

With the structure thus far described it will be observed that the several bunkers on each and on opposite sides of the ship may receive their supply of coal simultaneously, 60 or any particular bunker may receive its supply of coal without introducing the coal into the other bunkers, or the coal may be introduced into any desired number of bunkers on one or both sides of the ship at 65 the same time. It will be understood that in carrying out the above mentioned object the valves or gates 10 in the pipes or conduits 7 will be adjusted so as to admit or prevent the discharge of coal through the 70 said pipes or conduits and since these valves are independently adjustable, it will be manifest that the discharge of any particular hopper may be obtained without affecting the other hoppers.

Although the above described structure of collier renders as very simple the operation of coaling a ship and at the same time reduces to a minimum the time heretofore required for coaling ships, such structure 80 nevertheless provides a beam commensurate with the relatively great height of the collier above the water level and thus prevents the capsizing of the collier on a relatively high sea.

A buffer in the form of a series of upright planks 11 connected to horizontal rails 12, is arranged on the interior of and conforms to the inner contour of the collier as defined by the inner faces of the sides and bow, a plurality of springs 13 are interposed between the buffer and inner surface of the collier and operate to project the buffer and hold the same in spaced relation to the said inner surface. The springs are supported in any suitable manner such as by pins 14, connected to the buffer and passing through the springs and fitting in sockets in the sides 5—5 and bow 8, the said sockets being of such length as to admit of the inward movement of the pins under pressure on the buffer 11. Thus it will be seen that the buffer will act to reduce a strain on the sides or bow of the collier produced by contact with the ship to be coaled during the act of 90 warping the ship into the collier.

As before stated the collier is constructed with a view to accommodating ships of the greatest beam, it will be manifest, however, that when a ship of relatively small beam is warped into the collier considerable space will exist between the outer surface

of the ship and adjacent surface of the collier. Now even with large ships where a very small space will exist between the collier and the ship, it is desirable to guard 5 against relative movement of the collier and the ship, which would naturally result if the collier and ship were in a sea-way which would affect their stability, therefore in order to overcome such relative movement, 10 clamps in the form of strips 15—15 corresponding to the length of the sides 5—5 and screws 16—16 connected to the strips and screwed into boxings 17 on the deck, are provided for clamping the collier to the ship 15 to be coaled. The lengths of the screws are such as to admit of projecting the strips sufficiently far inward to effect contact with the sides of a relatively narrow vessel and although the screws may, if desired, be operated by hand, it is deemed advisable to provide means for turning the several screws simultaneously, such as by worm gearing 18, which includes shafts 19 splined in the worms 18, this gearing being connected to 20 a suitable motor arranged in the collier. 25

Although the collier is susceptible of being towed like the ordinary barge, yet if so desired and as shown in the drawings, the collier may carry its own motive power in 30 which event, the necessary mechanism to effect the turning of the propeller 20 is arranged in the bow portion 8 of the collier.

The rudders 21—21 are arranged on the sterns of the sides 5—5 and are operated by 35 any suitable mechanism from the pilot house 22.

In conclusion it may be stated that in addition to the improved coal delivering properties had by the device, the construction is 40 such as to admit of the easy loading of the hoppers when the device is arranged alongside a coal dock, and with the usual loading apparatus now employed in coal docks.

What is claimed as new is:

45 1. A collier comprising spaced side portions arranged so as to receive between them the ship to be coaled, a bow portion connect-

ing the side portions at one end, and coal pockets superimposed on the side portions.

2. A collier comprising spaced side portions arranged so as to receive between them the ship to be coaled, a bow portion connecting the side portions at one end, and a series of non-communicating coal pockets superimposed on the side portions. 50 55

3. A collier comprising spaced side portions arranged so as to receive between them the ship to be coaled, a bow portion connecting the side portions at one end, and a series of non-communicating coal pockets 60 superimposed on the sides and having adjustable delivery pipes to direct the coal into the ship between the sides. 65

4. A collier comprising spaced side portions arranged so as to receive between them the ship to be coaled, a bow portion connecting the side portions at one end, a series of non-communicating coal pockets superimposed on the sides and having adjustable delivery pipes to direct the coal into the 70 ship between the sides, and a gate or valve in each of such delivery pipes. 75

5. A collier comprising spaced side members arranged so as to receive between them the vessel to be coaled, a bow portion connecting the said side members at one end, a buffer yieldingly held in spaced relation to the inner faces of the side members and bow portion, and coal pockets superimposed 80 on the side members. 85

6. In a collier of the class described, the combination of side members arranged to receive between them a vessel to be coaled, clamping strips carried by the side members, and means for projecting said clamping strips into contact with the sides of the vessel arranged between the side members. 90

In testimony whereof I affix my signature in presence of two witnesses.

CHARLES PASQUIER.
